TRANSCEIVING CIRCUIT ARRANGEMENT

Adelbert van Weel, Eindhoven, Netherlands, assignor to Hartford National Bank and Trust Company, Hartford, Conn., as trustee

Application February 12, 1947, Serial No. 728,143
In the Netherlands July 28, 1944

Section 1, Public Law 690, August 8, 1946
Patent expires July 28, 1964

7 Claims. (Cl. 250—9)

1

My copending U. S. patent application 685,199 concerns a transceiving circuit arrangement for short waves, in which for reception use is made of two mixing systems, to whose input electrodes the incoming oscillations are fed in push-pull and the local oscillations are supplied in single phase, means being provided which permit the said mixing systems or a pair of push-pull connected high-frequency amplification systems preceding them to be coupled back in such a manner that these systems generate oscillations that may be transmitted by means of a dipole antenna.

In a particular form of construction of this circuit not only the push-pull circuit, through which the incoming oscillations are supplied to the mixing systems, is tuned to the frequency of the incoming oscillations, but also the single-phase circuit, through which the local oscillations are fed to the mixing systems, is tuned to the frequency of the local oscillations to be used for reception. Means are provided, moreover, to couple the mixing systems back in such a manner as to generate the local oscillations in the said single-phase circuit. The single-phase circuit consists of the parallel-connected impedances of both halves of the push-pull circuit, the parallel-connected input impedances of the two mixing systems and the impedances which the input circuits of the two systems have in common.

In the present case the expression "push-pull circuit" is to be understood to mean the assembly of impedances available between two not directly interconnected input electrodes of the mixing systems, in which circulate currents having the frequency of the incoming oscillations. The expression "input circuit of a mixing system" is to be understood to mean all impedances available between the input electrodes of the mixing system, in which circulate currents associated with this system and having the frequency of the local oscillations.

In the aforesaid particular form of construction of the transceiving circuit it is possible, in principle, to generate simultaneously both the oscillations to be transmitted (push-pull oscillations) and the local oscillations for reception (single-phase oscillations). This permits transmission and reception simultaneously without the need for changing-over. In practice, however, this proves to be dependent upon a very accurate adjustment of the circuit, which is very difficult to realize. Therefore, according to the invention, means are provided by which the circuit can automatically be changed over alternately from transmission to reception and conversely.

2

One form of construction of the circuit according to the invention comprises means which provide that, in the absence of a modulation signal to be transmitted, exclusively the single-phase oscillations are produced. On the appearance of a modulation signal exclusively, the push-pull oscillations are generated automatically, for instance by damping the single-phase circuit.

In another form of construction of the circuit according to the invention, means are provided which permit the circuit continuously to be changed over alternately from transmission to reception and conversely at a frequency outside the range of frequencies of the incoming or transmitted low frequency oscillations (alternating frequency).

In the first-mentioned form of construction of the invention, the circuit is normally adjusted for reception. At this time only single-phase oscillations are produced, these being used as local oscillations. As soon, however, as transmission is desired, which occurs, for instance, in a telephony transmitter when words are spoken into the microphone, the single-phase circuit is damped. Damping may, for instance, be effectuated by means of a diode. At this time push-pull oscillation instead of the single-phase oscillation are generated, so that the circuit is changed-over to transmission. When the modulation signal ceases, the damping of the single-phase circuit is automatically cut out and the circuit generates local oscillations, so that the circuit operates again as a receiver.

In the last-mentioned form of construction the circuit is continually changed-over—preferably at a supersonic frequency—from transmission to reception and conversely, which permits conversation from both sides in a normal way.

In this form of construction, as well as in the first-mentioned construction, the circuit is preferably adjusted in such manner as to generate under all circumstances one of the two oscillations (single-phase oscillation, push-pull oscillation) and so as to generate, exclusively by damping one circuit, the kind of oscillations pertaining to the other circuit.

Again, the circuit may either be adjusted in such manner that normally, such as is also the case in the first-mentioned form of construction, the single-phase oscillation is generated and the circuit passes over automatically to the other oscillation as soon as the single-phase circuit is damped, or the circuit may be adjusted in such a manner that it passes over automatically from one kind of oscillation to the other according

as to whether one or the other circuit is damped. In the last-mentioned form of construction both adjustments may be used.

To prevent two transceiving circuits associated with one transmission system from alternately transmitting simultaneously and receiving simultaneously so that no communication could be established, it is advantageous to make use of different alternating frequencies in the various interconnected transceiving circuits. Use is preferably made of alternating frequencies having widely divergent values.

As an alternative, use may be made of intersynchronized alternating frequencies in the various transceiving circuits forming parts of a particular transmission system in such a manner that when the signal transmitted by one circuit arrives at the other circuit, the last-mentioned circuit receives and conversely.

The automatic changing-over from transmission to reception and conversely may also be used in circuits in which the functions of the push-pull circuit and the single-phase circuit are changed.

In order that the invention may be clearly understood and readily carried into effect, it will now be set out more fully with reference to the accompanying drawings representing, by way of example, one embodiment thereof.

Figure 1 shows a schematic diagram of one embodiment of the invention; and

Fig. 2 shows a block diagram of a further embodiment of the invention.

Fig. 1 represents a transceiving circuit in which the dipole antenna 1', 1'' is used both for receiving and for transmitting oscillations. When it is used as a receiving antenna the incoming oscillations are fed through a Lecher line 2', 2'' to the input electrodes of two push-pull connected triodes 3', 3''. The Lecher line 2', 2'' is tuned, through the intermediary of a short circuit bridge 4, to the frequency of the incoming oscillations. The short-circuit bridge 4 is connected to earth through a variable impedance 5, and through a resistance 6 to a source of potential (not represented) which supplies a suitable negative bias for the control grids of the triodes 3', 3''.

A resonant circuit tuned to the intermediate frequency and consisting of two inductances 7', 7'' and two condensers 8', 8'' is connected in push-pull to the anodes of the two triodes. In series with coils 7', 7'' are connected high-frequency choke coils 9', 9'' which serve to prevent a transfer of the high-frequency oscillations to the receiver parts next to the mixing stage. The junction of coils 7', 7'' is connected to earth through a condenser 10, which practically constitutes a short-circuit with regard to the intermediate oscillations, and through a terminal 11 to the positive terminal of a source of anode potential (not represented). Furthermore, coils 7', 7'' are inductively coupled with a second intermediate frequency circuit which consists of a coil 12 and a condenser 13 from which the output voltage of the circuit is taken.

The leads connecting the anodes of the triodes 3', 3'' to the intermediate frequency circuit 8', 8'', 7', 7'' includes two coils 14', 14''; moreover, the junction of the cathodes is connected through a coil 15 to the junction of the capacities 8', 8''.

To supply as high as possible a voltage having the frequency of the local oscillations to the control grids of the mixing triodes, the single-phase input circuit, which consists of the series-connection of the impedance 5, the variable impedance

16 connected between the junction of the cathodes and earth, the parallel-connected impedances of both halves of the push-pull circuit and the parallel-connected input impedances of the two triodes, is tuned to the frequency of the local oscillations, for instance, by adjustment of the variable impedances 5 and 16. Moreover, by a suitable adjustment of the impedances 5 and 16, antenna 1', 1'' may be connected at a voltage node of the local oscillations, thus preventing the antenna from radiating these oscillations.

The inductance coils 14', 14'' inserted in the anode circuits of the triodes 3', 3'', together with the anode control-grid capacities of the triode systems, bring about such a feedback that these systems generate oscillations which vary symmetrically with respect to earth and are transmitted by the dipole antenna 1', 1''. These oscillations may, for instance, be modulated by supplying a variable anode voltage to the terminal 11.

The inductances 14', 14'' bring about a negative damping of the push-pull circuit, which leads to the production of the oscillations to be transmitted, and in addition a negative damping of the single-phase input circuit which is tuned to the frequency of the local oscillations. It is therefore possible for the circuit itself to produce the local oscillations. The tendency to generate in the same phase i. e. to produce the local oscillations, is further enhanced by the presence of the inductance coil 15. If this tendency is to be subdued the inductance coil 15 may be replaced by a condenser.

The circuit-arrangement is now adjusted in such manner that, normally, only single-phase local oscillations are produced; consequently the circuit acts normally as a receiver. Furthermore, the adjustment of the circuit is such that upon damping of the single-phase circuit the circuit arrangement immediately produces the push-pull oscillation. According to the invention this damping is automatically brought about as soon as a signal is to be transmitted. One and the other is realized by the circuit part on the left-hand side of the short-circuit bridge 4.

The signal to be transmitted is supplied to the terminals bearing the reference numeral 17 in the drawing and is fed, through a condenser 18, to the control grid of a triode 19. Between the control-grid and the cathode of this triode is connected a leakage resistance 20. The cathode lead of the triode 19 includes a resistance 21 which forms at the same time part of a circuit comprising a diode 22, a choke 23 and a resistance 24. The diode 22 receives, through a resistance 25 and the aforesaid choke 23, a positive voltage from a source of potential (not represented). The anode of the diode is connected to the short-circuit bridge 4 through a blocking condenser 26.

In the absence of a modulating signal, the cathode lead of the triode 19 is traversed by a comparatively strong current which causes, through the resistance 21, such a voltage loss that the diode 22 is not capable of carrying current, so that it cannot have a damping effect on the single-phase circuit. In this case, consequently, solely the local oscillations are generated and the circuit acts as a receiver.

As soon, however, as a modulation signal appears at the terminals 17, the control-grid of the triode becomes more negative, due to the rectification occurring; the current in the cathode lead of the triode 19 decreases, the voltage loss through the resistance 21 falls off and the diode

22 becomes conductive. Owing to this the single-phase circuit is strongly damped and the circuit immediately starts producing the push-pull oscillation which is transmitted by the antenna 1', 1''. If the modulating signal disappears the initial state is resumed and the circuit functions again as a receiver.

The aforesaid circuit may also be used in an arrangement which is continuously changed over alternately from transmission to reception and conversely at a frequency outside the range of frequencies of the incoming or transmitted low frequency oscillations. When supplying, in effect, a voltage having the alternating frequency instead of the modulating signal to the terminals 17, the circuit is continuously changed over from reception to transmission and conversely in the rhythm of this frequency, in the aforesaid manner. In this case, however, the condenser 18 must be omitted since in this form of construction no rectification should take place.

In this form of construction of the invention use may advantageously be made of intersynchronized alternating frequencies. To receive in this case, with both of the transceiving circuits of the transmission system, the emitted energy with as pleasant an effect as possible, we preferably proceed as follows.

In Fig. 2, the transceiving circuits are shown, one represented by A. In A, the alternating frequency is produced and used, whereas in the other circuit B a voltage having the alternating frequency is picked up, amplified and utilized. The periodical changing-over from transmission to reception and conversely in the circuit 13 may be displaced in phase with respect to the alternating frequency picked up, in such a manner that the reception of the transmitter A is a maximum at B.

After this the value of the alternating frequency is controlled at A in such a manner that the transmitter B is received with a maximum intensity at A. With this adjustment the alternating frequency, with which the circuit B is operated is, of course, also varied automatically.

Such a control is necessary in conjunction with the transit time of the electromagnetic waves between the two points A and B. If the alternating frequency is correctly adjusted, in accordance with what has been said above, this transit time substantially corresponds with half the period of oscillation or with an odd multiple of half the period of oscillation of the alternating frequency. In this case the energy issued by the transmitter A is completely captured by B, and conversely the energy issued by B is completely captured by A.

What I claim is:

1. Transceiver apparatus adapted selectively to generate high frequency oscillation and to mix incoming signals with a source of local oscillations comprising, first and second thermionic discharge systems having each a cathode, input electrode and output electrode, means to transfer the incoming signals to the input electrode-cathode circuit of the said first and second thermionic discharge systems in push-pull, single phase means to couple the source of local oscillations to the input-electrode-cathode circuit of the said first and second thermionic discharge systems, an output stage, means to couple the said output stage to the output electrode-cathode circuit of the said first and second thermionic discharge systems, back coupling means applied to the output electrode-cathode

circuit of the said first and second thermionic discharge systems whereby said thermionic discharge systems are caused to oscillate, a source of control signals, and means to damp the source of local oscillations in accordance with the said control signals, said latter means comprising a unidirectional conductor in parallel with the source of local oscillations and means to render the said unidirectional conductor conductive in accordance with the said control signals.

2. In a transceiver, a circuit arrangement adapted selectively to generate high frequency oscillation of a given frequency and to mix incoming signals with a source of local oscillations comprising, first and second thermionic discharge tubes having each a cathode, grid and anode, push-pull means to transfer the incoming signals to the grid-cathode circuit of the said first and second thermionic discharge tubes, single phase means to couple the source of local oscillations to the grid-cathode circuit of the said first and second thermionic discharge tubes, an output stage, means to couple the said output stage to the anode-cathode circuit of the said first and second thermionic discharge tubes, back coupling means applied to the anode-cathode circuit of the said first and second thermionic discharge tubes whereby said thermionic discharge tubes are caused to oscillate upon damping of the said source of local oscillations, a source of modulating signals, and means to damp the source of local oscillations in accordance with the said modulating signals, said latter means comprising a diode connected in parallel with the source of local oscillations and means to render the said diode conductive in accordance with the said modulating signal.

3. In a transceiver, a circuit arrangement adapted selectively to generate high frequency oscillation of a given frequency and to mix incoming signals of a given frequency with a source of local oscillations comprising, first and second thermionic discharge tubes having each a cathode, grid and anode, push-pull means to transfer the incoming signals to the grid-cathode circuit of the said first and second thermionic discharge tubes, single phase means to couple the source of local oscillations to the grid-cathode circuit of the said first and second thermionic discharge tubes, an output stage, means to couple the said output stage to the anode-cathode circuit of the said first and second thermionic discharge tubes, back coupling means applied to the anode-cathode circuit of the said first and second thermionic discharge tubes whereby said thermionic discharge tubes are caused to oscillate upon damping of the said source of local oscillations, a source of modulating intelligence having a given range of frequencies, means to apply said source of modulating intelligence to the said first and second thermionic discharge tubes, a source of control signals having a frequency other than that of the generated high frequency oscillation, of the incoming signals and the said source of modulating intelligence and means to damp the source of local oscillations in accordance with the said control signals, said latter means comprising a diode connected in parallel with the source of local oscillations and means to render the said diode conductive in accordance with the said control signals.

4. In a transceiver, a circuit arrangement adapted selectively to generate high frequency oscillation of a given frequency and to mix incoming signals having a different frequency with

a source of local oscillations comprising, first and second thermionic discharge tubes having each a cathode, grid and anode, means to transfer the incoming signals to the grid-cathode circuit of the said first and second thermionic discharge tubes in push-pull, single phase means to couple the source of local oscillations to the grid-cathode circuit of the said first and second thermionic discharge tubes, an output stage, means to couple the said output stage to the anode-cathode circuit of the said first and second thermionic discharge tubes, back coupling means applied to the anode-cathode circuit of the said first and second thermionic discharge tubes whereby said thermionic discharge tubes are caused to oscillate upon damping of the said source of local oscillations, a source of modulating signals, and means to damp the source of local oscillations in accordance with the said modulating signals, said latter means comprising a unidirectional conductor in parallel with the source of local oscillations, and means to render the said unidirectional conductor conductive in accordance with the said modulating signal.

5. In a transceiver, a circuit arrangement adapted selectively to generate high frequency oscillation of a given frequency and to mix incoming signals having a different frequency with a source of local oscillations comprising, first and second thermionic discharge tubes having each a cathode, grid and anode, means to transfer the incoming signals to the grid-cathode circuit of the said first and second thermionic discharge tubes in push-pull, single phase means to couple the source of local oscillations to the grid-cathode circuit of the said first and second thermionic discharge tubes, an output stage, means to couple the said output stage to the anode-cathode circuit of the said first and second thermionic discharge tubes, back coupling means applied to the anode-cathode circuit of the said first and second thermionic discharge tubes whereby said thermionic discharge tubes are caused to oscillate upon damping of the said source of local oscillations, a source of modulating intelligence having a given range of frequencies, means to apply said source of modulating intelligence to the said first and second thermionic discharge tubes, a source of control signals having a frequency other than that of the generated high frequency oscillation, of the incoming signals and the said source of modulating intelligence and means to damp the source of local oscillations in accordance with the said control signals, said latter means comprising a diode connected in parallel with the source of local oscillations and means to render the said diode conductive in accordance with the said control signals.

6. Transceiver apparatus adapted selectively to generate high frequency oscillation and to mix incoming signals with a source of local oscillations comprising, first and second thermionic dis-

charge tubes having each a cathode, grid and anode, means to transfer the incoming signals to the input electrode-cathode circuit of the said first and second thermionic discharge tubes in push-pull, single phase means to couple the source of local oscillations to the grid-cathode circuit of the said first and second thermionic discharge tubes, an output stage, means to couple the said output stage to the anode-cathode circuit of the said first and second thermionic discharge tubes, back coupling means applied to the anode-cathode circuit of the said first and second thermionic discharge tubes whereby said thermionic discharge tubes are caused to oscillate upon damping of the said source of local oscillations, a source of control signals of a given frequency, means to damp the source of local oscillations in accordance with the said control signals of a given frequency, said latter means comprising a diode in parallel with the source of local oscillations and means to render the said diode conductive in accordance with the said control signals, and a second transceiver apparatus having means to switch from transmission to reception selectively at a given frequency, said frequency being equal to the said control frequency.

7. Transceiver apparatus adapted selectively to generate high frequency oscillation and to mix incoming signals with a source of local oscillations comprising, first and second thermionic discharge tubes having each a cathode, grid and anode, means to transfer the incoming signals to the input electrode-cathode circuit of the said first and second thermionic discharge tubes in push-pull, single phase means to couple the source of local oscillations to the grid-cathode circuit of the said first and second thermionic discharge tubes, an output stage, means to couple the said output stage to the anode-cathode circuit of the said first and second thermionic discharge tubes, back coupling means applied to the anode-cathode circuit of the said first and second thermionic discharge tubes whereby said thermionic discharge tubes are caused to oscillate upon damping of the said source of local oscillations, a source of control signals of a given frequency, means to damp the source of local oscillations in accordance with the said control signals of a given frequency, said latter means comprising a diode in parallel with the source of local oscillations and means to render the said diode conductive in accordance with the said control signals, and a second transceiver apparatus located at a given distance and having means to switch from transmission to reception selectively at a given frequency, said frequency being equal to the said control frequency and being an odd submultiple of twice the period of the transit time to the said second transceiver.
